ington Corporation, Harrison, N.J., a corporation of
Delaware

Filed Dec. 16, 1965, Ser. No. 514,275
1 Claim (Cl. 165—113)

ABSTRACT OF THE DISCLOSURE

A vertical feedwater heater adaptable for two or more pass operation, having a construction which utilizes the pressure of steam entering the outer shell of the feed water heater to force condensate from the outer shell into and through a drain water cooler. The condensate passing through the cooler is cooled in two separate zones prior to its discharge from the feedwater heater. The forcing of condensate from the outer shell into the drain water cooler increase the heat transfer effectiveness of the feedwater heater.

This invention relates to new and improved drain coolers for use in vertical feedwater heaters.

A significant problem in the operation of the vertical feedwater heaters of the prior art, which employ drain coolers of conventional design, resides in the flooding of not insubstantial portions of the total available heat exchange surface areas of the heat exchange tubes by large amounts of condensate which accumulate in the lower portion of the outer shell adjacent the said drain coolers. Thus, the overall heat exchange tube surface area available for heat exchange duty is reduced to a correspondingly not insubstantial degree, and the overall heat exchange capacity of the vertical feedwater heater similarly reduced. It is, accordingly, a primary object of this invention to provide new and improved drain coolers, for use in vertical feedwater heaters, which substantially eliminate the problem of flooded, and accordingly wasted, heat exchange surface areas of the heat exchange tubes to result in vertical feedwater heaters of significantly increased heat exchange capacity without requiring any increase in the total available heat exchange surface areas of the heat exchange tubes.

Another object of this invention is the provision of new and improved drain coolers as above which result in vertical feedwater heaters of significantly increased heat exchange capacity without requiring any increase whatever in the overall size thereof.

Another object of this invention is the provision of new and improved drain coolers as above which are equally adaptable for use in vertical feedwater heaters of two or four pass design and provide, in both cases, for the efficient transfer of heat from the condensate to the feedwater within the said drain coolers.

A further object of this invention is the provision of new and improved drain coolers as above which are of decidedly uncomplicated design and construction, and which require the use of only relatively inexpensive, and readily available materials of proven dependability in the construction thereof, whereby the costs of fabrication, installation and maintenance thereof, and of the vertical feedwater heaters in which the same are utilized, are minimized, and long periods of satisfactory operation thereof assured.

The above and other objects and advantages of my invention are believed made clear by the following detailed description thereof taken in conjunction with the accompanying drawings wherein;

FIGURE 1 is a vertical cross-sectional view of a ver-

2

tical feedwater heater constructed in accordance with the teachings of the prior art;

FIGURE 2 is a vertical cross-sectional view of a two pass, vertical feedwater heater constructed in accordance with a first embodiment of my invention;

FIGURE 3 is a cross-sectional view taken along line 3—3 in FIGURE 2;

FIGURE 4 is a cross-sectional view taken along line 4—4 in FIGURE 3;

FIGURE 5 is a cross-sectional view of a second embodiment of my invention;

FIGURE 6 is a cross-sectional view taken along line 6—6 in FIGURE 5;

FIGURE 7 is a cross-sectional view taken along line 7—7 in FIGURE 6; and

FIGURE 8 is a cross-sectional view taken along line 8—8 in FIGURE 6.

Referring now to the drawings, a two pass, vertical feedwater heater of a design representative of the teachings of the prior art is indicated generally at 10, and comprises a shell 12 with a feedwater manifold 14 formed at the lower extremity thereof and separated therefrom by a tube sheet 16 extending thereacross as shown. A baffle plate 18 extends across the interior of the feedwater manifold 14 to devide the latter into a feedwater inlet chamber 20 and a feedwater outlet chamber 22. A plurality of heat exchange tubes 24 are supported from the tube sheet 16 and extend therefrom through the interior of the shell 12, with the inlet end of each of the said cooling tubes being in fluid flow communication with the feedwater inlet chamber 20, and the outlet end of each of the said tubes being in fluid flow communication with the feedwater outlet chamber 22.

A drain cooler 26 is formed within the shell 12 by a vertically extending baffle plate 28 which is supported from the tube sheet 16, and a plurality of baffles 30 which are supported in the depicted alternating manner from the walls of the said baffle plate and shell, respectively. A steam inlet 29 is provided in the upper portion of the shell 12, and a drain outlet 32 is provided in the lower portion of the said shell adjacent the tube sheet 16. Thus, feedwater under suitable pressure from any convenient source thereof may be supplied to the feedwater inlet chamber 20, flow therefrom through the interior of the outer shell 12 in first and second passes through the heat exchange tubes 24 as indicated by the arrows 34 and 36, respectively, to the feedwater outlet chamber 22. Concurrently therewith, steam at suitable temperature and pressure, from any convenient source thereof, may be introduced to the interior of the outer shell 12 through the steam inlet 29, flow into contact with the respective surfaces of the heat exchange tubes 24 through which the feedwater is flowing, and be condensed thereby, and collect as drain water, the surface of which is indicated at 38, in the lower portion of the outer shell 12 for the flow thereof through the drain cooler 26, as indicated by the arrow 40, from the outer shell 12 through the drain water outlet 32. Thus, although a good heat exchange relationship is provided by the counter-current flow of the feedwater and drain water through the baffled interior of the drain cooler 26, to result in initial heating of the said feedwater, a dead space of stagnated drain water, as indicated at 40, results whereby the condensing surfaces of the plurality of heat exchange tubes 24 which extend through the said pool of stagnated drain water, are completely wasted and the heat exchange efficiency of the second feedwater pass reduced accordingly.

An obvious, and currently widely utilized manner of offsetting this reduction in heat exchange efficiency is to increase the length of the heat exchange tubes to provide the required tube condensing surface area above the level of the condensed drain water which has collected in the

lower portion of the outer shell 12. This increase in the length of the respective heat exchange tubes 24 results not only in a significant increase in the space required for the installation of the vertical feedwater heater, but also, in a significant increase in the cost of fabrication of the said feedwater heater due to the greater amounts of material required for the construction of the longer heat exchange tubes 24, and the correspondingly longer outer shell 12. Thus is believed made clear that an increase in the length of the said tubes does not represent a satisfactory solution to the problem of wasted, cooling tube surface condensing area.

A satisfactory solution to the problem of wasted heat exchange tube surface area is, however, believed provided by applicant's invention which, as seen in the embodiment of FIGURES 2, 3 and 4, takes the form of a two pass, vertical feedwater heater 11 comprising a generally similarly arranged combination of correspondingly identified, vertical feedwater heater elements. In addition, the vertical feedwater heater 11 of the embodiment of FIGURES 2, 3 and 4, comprises a baffle plate 42 which extends in the depicted, generally radial manner, as best seen in FIGURE 2, from the interior wall of the outer shell 12 to the baffle plate 28 to thereby divide the interior of the drain cooler 26 into first and second chambers which are identified respectively as A and B.

A cover plate 44 extends as shown over the drain cooler 26 into contact with the adjacent upper extremity of the baffle plate 28 to thus seal the drain cooler from the remainder of the interior of the outer shell 12 and prevent the flow of condensed drain water from the former to the latter. A drain water inlet opening 46 is provided adjacent the lower extremity of the baffle plate 28 to permit the flow of drain water into the chamber A of the drain cooler 26, and a drain water transfer opening 48 is provided by the termination of the baffle plate 42 short of the under surface of the cover plate 44 to permit the flow of drain water from the chamber A of the drain cooler to the chamber B thereof.

In the embodiment of FIGURES 2, 3 and 4, the drain water outlet 32 (FIGURE 4) extends as shown from the cooler chamber B to the exterior of the vertical feedwater heater 11, whereby may be readily understood the manner in which the condensed drain water, as again indicated at 38 in FIGURE 3, may be collected in the lower portion of the outer shell 12 outside of the drain cooler 26, be forced by the pressure of the steam within the said outer shell to flow into chamber A of drain cooler 26 through drain water inlet opening 46 and substantially fill the said chamber, then flow from chamber A to chamber B through drain water transfer opening 48, and finally flow from the latter chamber to the exterior of the vertical feedwater heater through the drain water outlet 32 provided therefor in the exterior wall of the chamber B.

The pressure of the steam within the outer shell 12, the amount of drain water condensed per unit time, the total volume of the drain cooler 26, and the respective sizes of the drain water inlet opening 46, the drain water transfer opening 48, and the drain water outlet 32, are predetermined to both maintain the condensed drain water, within the outer shell 12 but without the drain water cooler 26, at the relatively low level thereof depicted in FIGURE 3, and to cause the said condensed drain water to substantially fill the interior of the said drain water cooler once steady state operational conditions have been reached by the feedwater heater 11.

Thus, the vertical feedwater heater 11 of FIGURES 2, 3 and 4 will provide parallel flow of the drain water and the feedwater which flow concurrently through chamber A of the drain water cooler 26, and will provide for counterflow of the said drain water and feedwater which flow concurrently through the interior of chamber B, to result in the efficient transfer of heat between the

said drain water and feedwater, and resultant preheating of the latter.

It has been determined by the actual taking of test data, and calculations based thereon, that the construction of FIGURES 2, 3 and 4 provides for approximately 70% of the total drain water cooling due to the parallel flow of the drain water and feedwater through chamber A of the drain water cooler 26, and approximately 30% of the total drain water cooling due to the counterflow of the drain water and feedwater through chamber B of the said drain water cooler. In addition, it has been determined that the weighted MTD of chambers A and B comprises 91% to 96% of the weighted MTD of the single chamber, one counterflow pass drain cooler arrangement of the prior art as depicted in FIGURE 1 and described in detail hereinabove.

Of additional significance, however, is the fact that the level of the condensed drain water within the interior of outer shell 12, but without the drain cooler 26 of the feedwater heater 11, is substantially lowered, as made clear by but a brief comparison of FIGURES 1 and 3, whereby the amount of dead space, and accordingly wasted condensing surface area of the heat exchange tubes 24, caused by the pool of stagnated drain water as indicated at 40 in FIGURE 1, is also substantially reduced to provide for a vertical feedwater heater 11 of significantly increased operational efficiency without attendant increase in feedwater heater size and cost of fabrication.

A four pass, vertical feedwater heater constructed in accordance with the teachings of applicant's invention is represented at 13 in the embodiment of FIGURES 5, 6 and 7, and, as seen therein, again comprises a generally similarly arranged combination of correspondingly identified, feedwater heater components. In this embodiment, however, the interior of the feedwater manifold 14 is divided, as best seen in FIGURE 8, by baffle plates 50 and 52 into a feedwater inlet chamber 54 with an inlet pipe 55 leading thereto, a feedwater transfer chamber 56, and a feedwater outlet chamber 58 with an outlet pipe 59 leading therefrom, respectively. This is made possible the flow of the feedwater through four passes during the traverse thereof of the vertical feedwater heater 13, with the said feedwater flowing from the feedwater inlet chamber 54 upwardly through those of the heat exchange tubes 24 in communication with the said inlet chamber for the first feedwater pass, downwardly through the same said heat exchange tubes into the feedwater transfer chamber 56 for the second feedwater pass, upwardly through the remainder of the heat exchange tubes 24 which are in fluid flow communication with the said feedwater transfer chamber for the third feedwater pass, and downwardly through the said heat exchange tubes into feedwater outlet chamber 58 for the fourth feedwater pass.

In this embodiment, the plurality of heat exchange tubes 24 are oriented differently relative to the chambers A and B of the drain cooler 26, with only the heat exchange tubes which function to convey the feedwater through the first and second passes thereof being arranged to pass through the drain cooler as made clear by FIGURE 7. The drain water flow through the said drain cooler is the same in this embodiment as it is in the embodiment of FIGURES 2, 3 and 4. Thus, the said drain water will again collect at a relatively low level, within the outer shell 12 but without the said drain cooler, as indicated at 38, be forced by the pressure of the steam within the said outer shell to flow into drain cooler chamber A through drain water inlet opening 46 extending there-between, then flow from drain cooler chamber A to drain cooler chamber B through drain water transfer opening 48 extending therebetween, and finally flow from drain cooler chamber B to the exterior of the feedwater heater 13 through drain water outlet 32. As a result, the said

drain water will again function to substantially fill the interior of the drain cooler 26 once steady state operation has been reached.

By this construction, counterflow of the drain water and feedwater, during the portions of both the first and second feedwater passes in which the feedwater passes through the drain cooler, is provided, with the feedwater flowing upwardly through drain cooler chamber B during the first pass thereof concurrently with the downward flow of drain water through the said chamber, and the feedwater flowing downwardly through drain cooler chamber A during the second pass thereof concurrently with the upward flow of the drain water through drain cooler chamber A. Thus is believed made clearly whereby the embodiment of FIGURES 5, 6 and 7 provide for the same significant saving in cooling tube condenser surface area in a four pass, vertical feedwater heater as does the embodiment of FIGURES 2, 3 and 4 in a two pass, vertical feedwater heater to again provide for significantly increased operational efficiency without attendant increase in the size and cost of fabrication of the said feedwater heater.

The actual taking of test data and calculations based thereon have established that the application of the teachings of applicant's invention to the construction of vertical feedwater heaters makes possible a reduction in the required, overall condensing surface area of the heat exchange tubes ranging from 3½% to 20%, whereby the amount of such condensing surface area required by vertical feedwater heaters of similar design of the prior art may be reduced by amounts within this same range without attendant reduction in the heat exchange capacity of the said vertical feedwater heaters.

Thus, for example, the application of the teachings of applicant's invention to a vertical feedwater heater of the prior art which requires 15,000 square feet of heat exchange tube condensing surface area to provide a required heat exchange capacity, can result in the saving of roughly 500 to 3,000 square feet of this tube condensing surface area to enable significant reduction in the size and cost of fabrication of the said vertical feedwater heater. In this regard, it is believed of interest to note that, in cases where stainless steel heat exchange tubes are required—the cost thereof being roughly \$10 per square foot of heat exchange tube condensing surface area—the saving of 500 to 3,000 square feet of heat exchange tube condensing surface area may readily be seen to result in a reduction in the cost of fabrication of the said vertical feedwater heater ranging from \$5,000 to \$30,000 per unit. For applications in which copper heat exchange tubes are satisfactory—the cost thereof being roughly \$6 per square foot of condensing surface area—cost reductions in the range of \$3,000 to \$18,000 per vertical feedwater heater unit are made possible.

It is to be understood that these cost reduction figures do not include the additional cost reductions made possible by the attendant reduction in the length of the outer shell 12, nor do they include the cost reductions made possible by the fact that the reduced size of the vertical feedwater heater enables the same to take up less space, which is, in many applications, at a decided cost premium.

It will be understood that the invention is not to be limited to the specific construction or arrangement of parts shown but that they may be widely modified within the invention defined by the claim.

Drain cooler shrouding may, if desired, be provided in both of the hereinabove-disclosed embodiments of applicant's invention in conventional, non-illustrated, manner to make possible the convenient removal of the major portion of the feedwater heater outer shell, in a manner well known to those skilled in this art, to enable the ready inspection and/or maintenance of the internal components of the respective feedwater heaters of the said embodiments.

What is claimed is:

1. In a vertical feedwater heater including an outer shell, a tube sheet in the lower portion of the outer shell, a plurality of heat exchange tubes extending from said tube sheet within said outer shell, means to flow feedwater in a plurality of passes through said heat exchange tubes including water box means associated with said tube sheet and said plurality of heat exchange tubes, partition means separating said water box means into at least first and second compartments, and feedwater inlet means in said second compartment, and means to introduce steam under pressure to said outer shell and condense said steam through contact with said heat exchange tubes, the improvement comprising:

means forming a closed drain cooler extending generally vertically in the lower portion of said outer shell, said drain cooler occupying less than the total area of said lower shell portion; generally vertical baffle plate means dividing said drain cooler into first and second zones;

at least one of said heat exchange tubes includes first and second spaced portions thereof which extend respectively through said first and second drain cooler zones;

at least one other of said heat exchange tubes includes spaced portions thereof adjacent said tube sheet which do not extend through either of said drain cooler zones;

outlet means in the lower portion of said second drain cooler zone for removing drain liquid therefrom;

passage means in the upper portion of the means dividing said drain cooler zones to allow drain liquid to flow from said first drain cooler zone to said second drain cooler zone;

inlet means in the lower portion of said first drain cooler zone communicating said remaining area of said lower shell portion with said first drain cooler zone to allow condensate which collects in the remaining area of said lower shell portion to enter said first drain cooler zone and, through the effect of the steam pressure in the outer shell, flow upwardly in said first drain cooler zone and then through said passage means to said second drain cooler zone whereby, large accumulations of condensate in said outer shell are prevented; and

each of said heat exchange tubes including first and second spaced portions extending respectively through said first and second drain cooler zones is connected to said tube sheet so that said second spaced portion of said heat exchange tube in said second drain cooler zone is in fluid flow communication with said second water box compartment and said first spaced portion of said heat exchange tube in said first drain cooler zone is in fluid flow communication with said first water box compartment, whereby the flow of feedwater through said second spaced portion of said heat exchange tubes is upward and flow through said first spaced portion is downward thereby producing countercurrent flow between the flow of feedwater in those portions of the heat exchange tubes which extend through said drain cooler.
